[57] ABSTRACT

A portable compactible hand loom includes an up-standing main frame, upper and lower spools rotatably and lockably mounted on the main frame and a tubular member tiltably mounted on the frame between the upper and lower spools, first and second elongated members in said tubular member in juxtaposed facing relationship, retaining means mounted on the tubular member for retaining said elongated members in juxtaposed facing relationship, each of said first and second members being connected at their adjacent ends to a heddle frame; the members being interconnected by a double ended lever connected through a shaft to a handle for producing relative movement of the first and second members, whereby a corresponding movement is produced in each frame to create a shed in a warp passing through the heddles for the passage of a weft.

HAND LOOM

BACKGROUND OF THE INVENTION

This invention relates to textile looms of the hand operated type.

It is an object of the present invention to provide a hand loom construction which may be easily operated with a minimum of instruction, and which can be used in the home and in occupational therapy.

It is another object of the invention to provide a loom which is relatively portable and which will conform to a compact arrangement for carrying.

It is a further object of the invention to provide a heddle frame for use in a hand loom.

SUMMARY OF THE INVENTION

According to one aspect of the invention a loom comprises a main frame, first and second heddle frames having heddles mounted therein, movably mounted on said frame, first and second members, said first member being connected to said first heddle frame and said second member being connected to said second heddle frame; retaining means for retaining said members in juxtaposed facing relationship during relative movement thereof, and means for moving said members simultaneously a predetermined distance in opposite directions, whereby a corresponding movement is produced in said heddle frames to create in use a shed in a warp passing through the heddles for the passage of a weft.

BRIEF DESCRIPTION OF THE DRAWINGS

A preferred embodiment of the invention is illustrated in the accompanying drawings in which:

FIG. 1 is a front elevation of a loom;

FIG. 2 is a rear elevation of the loom of FIG. 1;

FIG. 3 is a side elevation of the loom of FIG. 1;

FIG. 4 illustrates a detail of the loom of FIG. 1;

FIG. 5 illustrates a leaf spring;

FIG. 6 illustrates a heddle frame with heddles, and

FIG. 7 illustrates the loom of FIGS. 1 to 3 in a more compact position.

DESCRIPTION OF PREFERRED EMBODIMENTS

With reference to the drawings and particularly with reference to FIGS. 1 and 2, a loom 10 is shown in association with a bobbin 11. The loom 10 comprises an upstanding main frame 12, heddle frames 18 and 20 and a slide box 22.

The main frame 12 has a slot 24 defined in its upper end by means of which the loom 10 can be carried; main frame 12 is mounted on a base 26 having an integral upstanding flange 27 to which the main frame 12 is attached by a bolt.

A cord 106 is secured at one end to the base plate 26 its free end being adapted to cooperate with a latch 107 to hold it securely.

An upper spool 28 on which the warp yarn 29 is wound is mounted on a threaded shaft 28b secured to the frame 12 and is held firmly by a wing nut 28a, and a lower spool 32 on which woven fabric is wound is mounted on a threaded shaft 32b secured to the frame 12 and is held firmly by a wing nut 32a. A breast bar 30 having a collar 31 at its extremity, and a peg 34 project from the frame 12. A spool handle 35 is mounted on upper spool 28 and a spool handle 37 is mounted on lower spool 32.

The slide box 22 comprises upper and lower walls 23 and 25 and front and rear walls 123 and 125; slide box 22 is secured to frame 12 by connections 101 and 102, which cooperate with rear wall 125 and are described in greater detail below.

The slide box 22 as shown in FIG. 1 and FIG. 4 has projecting from it and partially contained within it a first member 40 and a second member 42 held in juxtaposed relation by wooden leaf springs 44, mounted by conventional means, for example, a nut and bolt connection to upper and lower walls 23 and 25. Mounted on each of members 40 and 42 is a projection 46 of a generally triangular shape; the projections are interconnected by a double-ended lever 48 mounted on a tapered shaft 50 having a threaded outer end.

A circular hole 148 is defined in each end of the lever 48 through each of which passes pin 146 connected to the triangular projections 46.

A link 55, which is bolted to a handle 57 for operation of the loom is held on the tapered shaft 50 by a nut fastened on the threaded portion.

Members 40 and 42 are connected, respectively, to heddle frames 18 and 20 such that the simultaneous movement of members 40 and 42 in opposite directions produces a corresponding movement in heddle frames 18 and 20.

Member 40 includes elongated recesses 59 in spaced apart relationship along its length; similar elongated recesses 61 are defined in member 42. Each recess 59 faces a similar recess 61; contained between each of a pair of facing recesses 59 and 61 is a nylon roller 63. The rollers 63 are rotatably mounted on pins 63a and 63b respectively; pin 63a is mounted on rear wall 125 and pin 63b is mounted on shaft 50. The rollers 63 provide smooth relative movement between members 40 and 42, and define the limits of relative movement of the members 40 and 42. Finally, the members 40 and 42 have channels 66 defined therein. The channels 66 are adopted to engage nylon rollers 65 mounted in the wooden leaf springs 44 at the extreme ends of relative movement of the members 40 and 42.

With reference to FIG. 5 a wooden leaf spring 44 includes a spring arm 77 and a head 79 in which is mounted, optionally rotatably, nylon roller 65.

With reference to FIG. 6 a heddle frame 18 is a rigid three-sided frame 68 composed of sides 68a and 68b and 68c; an elongated plate 69 is slidably mounted to form a fourth side of the frame 68 on a pair of rods 71, which pass through holes in the plate 69, and corresponding bores in the frame 68 in side 68b. Mounted in the frame 68 is a plurality of heddles 70.

Each heddle 70 comprises straight portions 70a with an eyelet 72 in the middle. At each end of the straight portions 70a there is a rod engaging means 73, which may suitably comprise a ring attached to the ends of the straight portions 70a, or where the heddle 70 is produced by stamping from metal sheet may be formed unitarily with the straight portions 70a; the rod engaging means 73 slide on the rods 71 to mount the heddle 70 in the frame 68.

Spacers 74 may be mounted on the rods 71 between the rod engaging means 73 to produce a desired spacing between adjacent heddles 70.

A retainer 75 with a spring clip 75a is secured between the ends of the rods 71 to prevent the plate 69 from sliding off during adjustment.

Secured to the ends of the frame 68 is a pair of studs 76 comprising a body portion 76a and a recessed portion 76b. The studs 76 are adapted to pass through holes in the plate 69, and the plate 69 is held firmly against the frame 68 by a clip 177, which engages the recessed portions 76b; FIG. 6 shows a slightly exploded view of this.

With reference to FIG. 7 the loom is shown in a more compact position wherein the slide box 22 and members 40 and 42 contained therein are held at an angle to the horizontal working position. This position is achieved by removing connection 101, which suitably comprises a bolt 101a adapted to cooperate with a threaded member 101b, for example, a nut located in the rear wall 125 of the slide box 22. Connection 102 suitably comprises a nut 102a and bolt 102b, the head of the bolt 102b being secured in the rear wall 125 of the slide box; loosening of the nut 102a on the bolt 102b permits the slide box to rotate on the bolt 102b to the more compact position shown in FIG. 7 for carrying and storage.

The bolt 101a may suitably be passed through holes in the ends of the members 40 and 42.

In the compact position illustrated in FIG. 7, a part of the rear wall 125 is held in a space between the upper spool 28 and the frame 12; this space is formed by enlarging the space 100 shown in FIG. 3 by displacing the upper spool 28 on its threaded mounting shaft 28a by unfastening the wing nut 28a by an appropriate amount. The wing nut 28a can then be lightly fastened to hold the rear wall 125 and hence the slide box 22, firmly in the compact position.

In addition to the compact position illustrated in FIG. 7, the loom 10 can be further compacted by removing the base plate 26 and securing it in face-to-face relationship with the frame 12. This is achieved by unfastening the bolt, securing flange 27 of the base plate 26 to the frame 12 and fastening the base plate 26 to the frame 12 by means of the same bolt through a hole (not shown) in the base plate 26. In addition, the handle 57 can be readily dismantled and held between the base plate 26 and the frame 12 in the compact position.

In operation, the warp yarn 29 is fed from upper spool 28 over breast bar 30 to the heddle frames 18 and 20. The warp yarn 29 is fed through heddle frame 18 so that a first yarn passes through the space between the first two adjacent heddles 70 and an adjacent yarn is passed through the eyelet 72 of the second heddle 70 and so on such that a first set of alternate yarns pass through spaces between heddles 70 and a second set of alternate yarns pass through eyelets 72. When the yarns are passed through heddle frame 20, the positions of the yarns are changed so that the first yarn passes through an eyelet 72 and the adjacent yarn passes through a space between two heddles 70. Thus each strand passes through a space between two heddles 70 in one of the heddle frames 18 and 20 and an eyelet 72 in the heddles 70 in the other of the heddle frames 18 and 20.

Feeding of the warp yarn 29 through the heddles 70 in the heddle frames 18 and 20 is facilitated by displacement of plate 69 on rods 71 so that the heddles 70 may be separated.

When the warp yarn 29 has passed through the heddles 70 of heddle frames 18 and 20, the yarns are tied together at their ends, passed under peg 34 and wound on the lower spool 32.

The collar 31 prevents the warp yarn from sliding over the edge of breast bar 30.

The free end of the cord 106 is secured with the latch 107 to provide a loop. The operator of the loom holds the loom firmly by inserting his foot in the loop and applying pressure after adjustment of the loop length to his requirements.

An up and down movement of handle 57 produces a simultaneous and opposite movement in first and second members 40 and 42 through the double-ended lever 48; during the movement the pins 146 contact and move along the portion of the circumference of the holes 148 adjacent the ends of lever 48, the edge of each hole 148 pushes on the contacting pin 146 and helps to keep the members 40 and 42 in engagement with the rollers 63.

The movement of members 40 and 42 produces an equivalent movement in heddle frames 18 and 20 whereby a shed 74 is produced in the warp yarn 29 through which the bobbin 11 containing the weft yarn 33 is passed. The procedure is repeated with the bobbin 11 being passed through the shed 74 formed each time that the relative position of heddle frames 18 and 20 is changed by movement of the handle 57.

The woven fabric 175 thus formed is wound onto the lower spool 32 by unfastening wing nut 32a and rotating lower spool 32 on its shaft 32b by means of spool handle 37. Fresh warp yarn 29 is unwound from upper spool 28 by unfastening wing nut 28a and rotating upper spool 28 on its shaft 28b by means of spool handle 35.

It will be apparent that the loom according to the invention can be operated without difficulty by relatively inexperienced people.

I claim:

1. A portable compactible hand loom comprising a main frame, first and second heddle frames, having heddles mounted therein, movably mounted on said frame, first and second members, said first member being connected to said first heddle frame and said second member being connected to said second heddle frame; said first and second members having facing sides with facing recesses defined therein and a roller member contained in said facing recesses; retaining means for retaining said members in juxtaposed facing relationship during relative movement thereof, and means for moving said members simultaneously a predetermined distance in opposite directions, whereby a corresponding movement is produced in said heddle frames, to create in use a shed in a warp passing through the heddles for the passage of a weft.

2. A loom according to claim 1 wherein said first and second members pass through and extend from a hollow open ended member mounted on said main frame and said retaining means are mounted on upper and lower surfaces of said hollow open ended member.

3. A loom according to claim 2 wherein each of said retaining means comprises an elongated spring arm mounted at one end to said hollow open ended member, the other end of said arm including a retaining head containing means adapted to engage said first and second members respectively, said first and second members each having a groove defined therein for receiving said means at the predetermined extremities of relative movement of said first and second members thereby defining the extremities of relative movement of said first and second members.

4. A loom according to claim 2 wherein a spool for holding warp yarn is rotatably mounted on said main frame on a shaft connected to said main frame, said spool being displaceable along said shaft to define an enlarged space between said spool and said main frame; said hollow open ended member being tiltable between a working position and a compact position wherein a portion of said hollow member is retainable in said enlarged space.

5. A portable compactible hand loom comprising an upstanding main frame, upper and lower spools rotatably and lockably mounted on said main frame, a tubular member tiltably mounted on said main frame between said upper and lower spools, first and second elongated members in said tubular member in juxtaposed facing relationship, retaining means mounted on said tubular member for retaining said elongated members in juxtaposed facing relationship, each of said first and second members being connected at their adjacent ends to a heddle frame; said members being interconnected by a double ended lever connected through a shaft to a handle for producing relative movement of said first and second members, whereby a corresponding movement is produced in each heddle frame to cre-

ate a shed in a warp passing through the heddles, for the passage of a weft.

6. A loom according to claim 5 wherein facing sides of said first and second members have facing recesses defined therein, and a roller member contained between said facing recesses for smooth relative movement of said members.

7. A loom according to claim 6 wherein each of said heddle frames comprises a frame, having two exposed ends, a pair of spaced apart rods mounted in said frame, a member slidably mounted on said rods adapted to contact said exposed ends, holding means for holding said member in contact with said exposed ends; a plurality of spaced apart heddles each having an eyelet therein and a rod engaging means at each extremity, said heddles being mounted on said rods by means of said rod engaging means.

8. A loom according to claim 7 wherein said holding means comprises a pair of studs extending from said exposed ends of said frame through holes defined in said member each stud having means therein for engaging a part of an elongated clip adapted to hold said member.
